UNITED STATES PATENT OFFICE

OTTO EBERSPACHER, OF ANGLETON, TEXAS

AUTOMATIC CONTROL VALVE

Application filed July 22, 1930. Serial No. 469,717.

This invention relates to new and useful improvements in an automatic control valve.

One object of the invention is to provide a mechanism of the character described specially designed for use in connection with water heaters wherein gas is used as a fuel and whereby the valve controlling the supply of the fuel will be automatically opened to permit gas to flow to the burner when the corresponding water faucet is opened and whereby the supply of gas to the burner will be automatically cut off when said service faucet is closed.

Another object of the invention is to provide means for automatically controlling the gas line valve in accordance with varying pressures in the water supply line through which water is supplied to the burner coil and to the service faucet.

With the above and other objects in view the invention has particular relation to a novel construction, operation and arrangement of parts, an example of which is given in this specification and illustrated in the accompanying drawing, wherein:

The figure shows a vertical sectional view of the valve and the controlling mechanism therefor, and the associated heater coil and burner.

In the drawing, the numeral 1 designates the heater coil, underneath which there is located any conventional type of gas burner 2, which is supplied with fuel through the gas line 3. Incorporated into this line there

is a valve casing 4 having a seat 5 therein which is controlled by the valve 6. This valve is attached to the lower end of the stem 7 which works through the stuffing box 8 in the casing 4 and whose upper end is attached to

a plunger 9 which works through the stuffing box 10 of the cylinder 11. This cylinder is anchored in relation to the casing 4 by a suitable yoke 12 and the cylinder 11 is incorporated into the water supply line 13 which terminates in the coil 1. Leading from this coil there is a service line 14 which is controlled by a suitable valve or faucet 15.

The end of the plunger in the cylinder 11 is formed into a piston 16 which includes a cup ring 17 secured in place by the annular

plate 18 having the threaded shank 19 which is threaded into the plunger to clamp the cup ring in place. The cylinder has a removable end plate 20 and the clamp plate 18 carries a conical shaped head 21 whose outer end is adapted to about the end plate 20.

The piston 16 has an opening 22 therethrough, and a valve stem 23 is anchored at one end to the end plate 20 and extends through said opening and its other end carries the stationary valve 24. The water supply line enters the cylinder 11 on one side of the piston 16 and leads out of said cylinder on the other side of said piston.

When the service faucet 15 is closed, pressure of the water will build up in the cylinder 11 on both sides of the piston 16, but the area of said piston, exposed to such pressure, is greater on the side thereof opposite the valve 24 than that on the side adjacent said valve 24. This unequal pressure will operate to force the piston 16 toward the valve 24 and the opening 22 will be closed by said valve and the gas valve 6 will be seated on the seat 5 and the supply of gas to the burner will be cut off. When the service faucet is open, the pressure against the outer side of the piston 16 will be relieved and the pressure of the water on the other side of the piston will operate to lift said piston from the valve 24, admitting water through the opening 22 to the coil and thence to the service faucet and at the same time lifting the valve 6 from the seat 5 and admitting gas to the burner.

From an inspection of the drawing it will be observed that the valve 24 is of such size as to fit loosely in the opening 22 and when the piston 16 is moved downwardly by the pressure above it, and will move down over said valve 24, in other words said valve 24 will then extend up into the opening 22, but will permit sufficient leakage to equalize the pressure on opposite sides of the piston. This construction is provided so that when the faucet 15 is open, the piston 16 will move upwardly a sufficient distance to fully open the valve 6 before the valve 24 opens the opening 22.

The drawing and description disclose what

is now considered to be a preferred form of the invention by way of illustration only, while the broad principle of the invention will be defined by the appended claims.

What I claim is:

5 1. In combination, a gas valve for controlling the flow of gas to a burner, a cylinder having a water inlet port and a water outlet port, a movable plunger whose inner end is formed into a piston in the cylinder between said ports and having an opening for the passage of water from the inlet to the outlet port, a stationary valve arranged to partially close said opening when the piston is moved 10 to one position and to fully open said opening when the piston moves to another position, and a stem connecting the gas valve directly to the plunger.

2. In combination, a valve for controlling 20 the flow of gas through a line, a cylinder having an inlet port from a water supply line and an outlet port to a water service line, means for closing said service line, a movable partition in the cylinder between said 25 ports, said partition having a smaller area exposed to water pressure on the inlet port side than on the outlet port side, a connection between the partition and gas control valve effective to close said gas control valve when 30 said service line is closed, said partition having an opening to permit the flow of water from the inlet port to the outlet port, and a fixed valve arranged to only partially close 35 said opening when the gas control valve is closed and to maintain said opening so partly closed until the valve is fully opened.

3. In combination, a valve for controlling 40 the flow of gas through a line, a cylinder having an inlet port from a pressure fluid supply line and an outlet port to a service line, means for controlling said service line, a movable partition in the cylinder between 45 said ports and having an opening therethrough and having a greater area, exposed to fluid pressure, on one side than on the other side, a conical head on the side of said partition having the greater area arranged to abut the opposing end of the cylinder, said partition being operable solely by the pressure 50 of the fluid in said cylinder, a valve fixed in the cylinder and shaped to only partly close said opening when the partition is in one position and to fully open said opening when said partition is in another position and 55 a connection between said partition and said gas controlling valve.

4. In combination, a gas valve for controlling the flow of gas to a burner, a cylinder having a water inlet and outlet, a movable piston in the cylinder between said inlet and outlet said piston having an opening for the passage of water from said inlet to said outlet a stem connecting the piston to said 60 gas controlling valve and effective to open and close said valve, a valve in the cylinder 65

arranged to partially close said opening in advance of the closing of the gas controlling valve and to maintain said opening so partially closed until the gas controlling valve is fully opened and to fully open said opening. 70

5. In combination a gas valve for controlling the flow of gas to a burner, a cylinder having a water inlet and outlet and having a stuffing box on one end and a head at the 75 other end, a plunger working through said stuffing box and having a piston thereon movable in the cylinder between said inlet and outlet said piston having an opening for the passage of water from said inlet to the outlet, a stop on said piston arranged to abut said head, a stem connecting the piston to the gas controlling valve and effective to open and close said valve, a stem connected to said head and extending through said 80 opening, a valve on said last mentioned stem arranged to partly close said opening when the piston is in one position and arranged to clear said opening only when said piston has moved to another position. 85

In testimony whereof I have signed my name to this specification.

OTTO EBERSPACHER.
